US00D744794S

(12) **United States Design Patent**
Elliston et al.(10) **Patent No.:** **US D744,794 S**
(45) **Date of Patent:** **** Dec. 8, 2015**(54) **RECIPROCATING SAW BLADE**(71) Applicant: **Irwin Industrial Tool Company**,
Huntersville, NC (US)(72) Inventors: **Asif Elliston**, Springfield, MA (US);
Charles E Kalomeris, E. Longmeadow,
MA (US)(73) Assignee: **Irwin Industrial Tool Company**,
Huntersville, NC (US)(**) Term: **14 Years**(21) Appl. No.: **29/498,538**(22) Filed: **Aug. 5, 2014**

European Search report for European Application No. EP 13 00 0580,
dated Apr. 10, 2013.*Primary Examiner* — Elizabeth Albert(74) *Attorney, Agent, or Firm* — Sutherland Asbill &
Brennan LLP(57) **CLAIM**The ornamental design for a reciprocating saw blade, as
shown and described.**DESCRIPTION**FIG. 1 is a perspective view of a reciprocating saw blade;
FIG. 2 is a front elevational view thereof, the rear elevational
view being a mirror image thereof;

FIG. 3 is a top plan view thereof;

FIG. 4 is a bottom plan view thereof;

FIG. 5 is a left side elevational view thereof; and,
FIG. 6 is a right side elevational view thereof.All front and rear surfaces are claimed up to the edges shown
in broken lines. The broken lines in FIGS. 1 to 4 are included
to show portions that form no part of the claimed design.**1 Claim, 2 Drawing Sheets**(56) **References Cited**
